UNITED STATES PATENT OFFICE.

WILLIAM HORACE STEVENTON, OF BURSLEM, STOKE-ON-TRENT, ENGLAND.

DESIGN FOR A PLATE OR SIMILAR ARTICLE.

Application filed February 23, 1929. Serial No. 30,183. Term of patent 3½ years.

To all whom it may concern:

Be it known that I, WILLIAM HORACE STEVENTON, a subject of the King of Great Britain and Ireland, and resident of Burslem, Stoke-on-Trent, in the county of Stafford, England, have invented a new, original, and ornamental Design for a Plate or Similar Article, of which the following is a specifica-

tion, reference being had to the accompanying drawing, forming part thereof, which drawing is a face view of a plate or similar article illustrating my new design.

I claim:

The ornamental design for a plate or similar article, as shown.

WILLIAM HORACE STEVENTON.
